ANGELO FUSARY, OF NEW YORK, N. Y.

Design No. 4,750, dated April 4, 1871.

DESIGN FOR A STATUE.

The Schedule referred to in these Letters Patent and making part of the same.

To all whom it may concern:

Be it known that I, ANGELO FUSARY, of the city, county, and State of New York, have invented a new and original Design for Statuary; and I do hereby declare that the following is a full, clear, and exact description thereof which will enable others skilled in the art to make and use the same, reference being had to the accompanying drawings forming part of this specification.

The nature of my design is fully represented in the accompanying photographic illustrations, to which reference is made.

I claim as my invention the design as shown.

The above specification of my invention signed by me this 18th day of February, 1871.

ANGELO FUSARY.
